ENVELOPE

Luther G. Simjian, Greenwich, Conn., assignor to Universal Match Corporation, St. Louis, Mo., a corporation of Delaware

Filed Oct. 9, 1963, Ser. No. 314,945

4 Claims. (Cl. 229—68)

This application is a continuation-in-part of Serial No. 288,105, filed on June 17, 1963, now abandoned.

This invention relates to packaging devices and more particularly to an envelope for transporting documents.

The envelope of this invention is especially suited for use with a bank depository machine of a type similar to that disclosed in U.S. Patent No. 3,076,965, granted to me on February 5, 1963. This type of machine is adapted to receive an envelope containing a plurality of documents, such as paper currency and checks, to extract the paper currency and checks from the envelope, to individually photograph and to store the paper currency and checks, and to provide a receipt for the transaction.

By such an arrangement, the depositor may at his convenience insert the paper currency and checks which he intends to deposit into the envelope and seal the envelope. The envelope may then later be personally inserted into the depository machine by the depositor; or it may be sent through the mails to the bank, wherein the envelope, without being first opened, is inserted into the depository machine.

It is, therefore, an object of this invention to provide an envelope for transporting documents, which envelope may be automatically opened by a machine and the documents extracted without the possibility of damage to the documents.

Another object is to provide an envelope which automatically creates an identification sheet which may be extracted with the other contents from the envelope.

A further object is to provide an envelope for enclosing documents, which envelope may be opened by mechanical means and the documents extracted and recorded without human intervention.

A feature of this invention comprises a pair of outer panels joined or joinable along their perimeters, one portion of the perimetrical juncture including a multifold arrangement, and a baffle panel disposed between said outer panels and forming a document receiving enclosure with one of said outer panels, one edge of said baffle panel interengaged with said multifold arrangement so as to guide an opening means thrust through said multifold arrangement away from the documents.

These and other objects and features of this invention will become more apparent by reference to the following description taken in conjunction with the accompanying drawings, in which:

FIGURE 1 is a plan view of an assembled envelope illustrating a first embodiment of this invention;

FIGURE 2 is a plan view of a blank which, when assembled, forms the envelope of FIGURE 1;

FIGURE 3 is a front view in cross-section, on an enlarged scale, taken along line 3—3 in FIGURE 1;

FIGURE 4 is an end view in cross-section, on an enlarged scale, taken along line 4—4 in FIGURE 1;

FIGURE 5 is a plan view of an assembled envelope illustrating a second embodiment of this invention;

FIGURE 6 is a plan view of a blank which, when assembled, forms the envelope of FIGURE 5;

FIGURE 7 is a front view in cross-section, on an enlarged scale taken along line 7—7 in FIGURE 5;

FIGURE 8 is an end view in cross-section, on an enlarged scale, taken along line 8—8 in FIGURE 7; and

FIGURE 9 is a sectional view of a detail of an additional modification of this invention.

2

Turning to the drawings, an envelope 10 is shown assembled and sealed in FIGURE 1. This envelope is formed from a single blank of paper 12, as shown in FIGURE 2.

The paper blank 12 includes a first quadrilateral panel 14, a second quadrilateral panel 16 joined to the panel 14 at a fold line 18, and a quadrilateral baffle panel 20 joined to the panel 16 at a fold line 22. The panels 14 and 16 are substantially symmetrically identical about the axis of symmetry provided by the fold line 18. The panels 14, 16, and 20 are here shown as rectangles, however, it is within the ambit of this invention to utilize other geometric shapes.

A side flap 24 is joined to the panel 14 at a fold line 26. A top flap 28 is joined to the panel 14 at a fold line 30. A multifold plait 32 is provided by a leg panel 34 which is joined to the panel 14 at a fold line 36, a leg panel 38 which is joined to the panel 34 at a fold line 40, and a side flap 42 which is joined to the panel 38 at a fold line 44.

A strip of adhesive is provided along the distal edge of the side flap 24, at 46, and along the distal edge of the top flap 28, at 48. A narrow strip of adhesive is provided along each side of the fold line 36 on the panel 14, at 50, and on the panel 34, at 52. A narrow strip of adhesive is provided along the fold line 44 on the panel 38, at 54, and adhesive is provided over the full surface of the side flap 42. The adhesive is applied to the upper surface of the paper blank 12, as shown in FIGURE 2, and this upper surface will generally form the inner surfaces of the envelope 10.

The paper blank 12 is folded concavely along the fold lines 18, 22, 26, 30, 36, and 44, and is folded convexly along the fold line 40. As is shown in FIGURES 1, 3, and 4, when the envelope is assembled, the panel 14 forms the envelope's outer bottom wall, the panel 16 forms the outer top wall, and the panel 20 is disposed between these two walls in the enclosure provided thereby. The side flap 24 is folded over and secured to the outer surface of the panel 16. The fold line 36 forms the vertex of a first externally directed fold, the fold line 40 forms the vertex of a mediate, internally directed fold, and the fold line 44 forms the vertex of a second externally directed fold. The side flap 42 is folded over and secured to the outer surface of the panel 16. The vertex of the first fold is made rigid by the adhesive strips 50 and 52 which are adhered to each other. Similarly, the vertex of the second fold is given rigidity by the adhesive strip 54 which is adhered to the inner surface of the panel 16. The left edge of the baffle panel 20 is disposed into the first fold, as shown in FIGURE 3, but is not joined thereto.

The baffle panel 20 and the outer panel 14 form a sub-enclosure which is adapted to receive a plurality of documents, shown in FIGURE 4 as a single document 56.

For the purposes of automatic machine handling, an indicium adapted to be sensed is provided on the assembled envelope to indicate the orientation of the envelope. This indicium is here shown as two notches 58 and 60 cut into the edges of the two externally directed folds, as shown in FIGURES 1 and 3. In FIGURE 3 the notch through the first fold is shown as 58a, and the notch through the second fold is shown as 58b. These notches are made narrower than the width of the adhesive strips 50, 52, and 54, so that these notches do not form openings into the interior of the envelope 10. Other means may be used for determining the proper orientation of the envelope, for instance, a color mark which is adapted to be sensed by photo-electric means, or a protrusion adapted to be sensed by a mechanical switch arm.

It is desirable to have a tally sheet bearing the depositor's name and address handled by the depository machine together with the enclosed documents. For this purpose a portion 62 of the upper surface of the panel 16 is coated with carbon or a chemical agent for transferring impressions. When the depositor writes his name and address on the outer surface of the panel 16, as shown in FIGURE 1, the impression of this writing will be reproduced on the baffle panel 20. When the panel 20 is severed from the panel 16, as will be described below, this baffle panel will serve as a tally sheet and will be removed from the envelope with the other document.

It is also desirable to have the tally sheet serve as an itemized listing of the documents enclosed. To accomplish this, the flap 28 is formed of greater length, as shown in the dotted lines in FIGURE 1 at 64. The listing is written out by the depositor on the outer surface of the panel 16, above the name and address, in the area which will be covered, as will be described below, by the flap 28. The impression of this listing will also be reproduced on the baffle panel 20. The adhesive strip 48 is arranged so that when the flap is sealed, the strip 48 will be disposed between the area for the name and address and the area for the listing.

In use, the depositor writes his return address and the itemized listing of enclosed documents on the outer surface of the panel 16. The documents are inserted into the enclosure formed by the panel 14 and the baffle panel 20, and the flap 28 is folded over and secured to the outer surface of the panel 16, thereby sealing the documents in the envelope. It may be noted that the only space presented to the depositor for insertion of documents is the space between the panel 14 and the baffle panel 20. The space between the panel 16 and the baffle panel 20 is concealed and is inaccessible. When the envelope is received by the depository machine, the notches 58 and 50 are sensed by the machine to properly orient the envelope for opening. An opening means, such as a blade-like element, shown in FIGURE 3 in dotted lines at 66, is thrust at the multifold plait of the envelope substantially at the fold line 40. The blade-like element passes between the two externally directed folds and cuts through and severs the internally directed fold. As the blade-like element passes into the interior of the envelope it is deflected by the baffle panel 20 away from the documents, and passes between the baffle panel 20 and the panel 16. It may be noted that by virtue of the left edge of the panel 20 being tucked into the first fold, the blade-like element is precluded from engaging this edge, or more than glancing against the surfaces of the panel 20, and is, therefore, precluded from striking the enclosed documents. The fold lines 18, 26, 40, and the adjacent fold lines 22 and 30 are subsequently severed, leaving the envelope open along all four edges. The documents and the severed baffle panel 20 are now removed. Typical envelope opening means comprise, aside from the blade-like instrument indicated, a pivoted shearing mechanism, and a movable wire instrumentality. In each instance, however, the fold acts as an entrance guide for the cutting instrumentality and the baffle panel shields the documents from this instrumentality.

The envelope 210 of the second embodiment, shown in FIGURES 5, 6, 7, and 8, is formed from a paper blank 212 which includes a first panel 214, a second panel 216 joined to the panel 214 at a fold line 218, and a baffle panel 220 joined to the panel 216 at a fold line 222.

A first multifold plait 232 is provided by a leg panel 234 which is joined to the panel 214 at a fold line 236, a leg panel 238 which is joined to the panel 234 at a fold line 240, and a side flap 242 which is joined to the panel 238 at a fold line 244. A second multifold plait 232' is provided by a leg panel 234' which is joined to the panel 214 at a fold line 236', a leg panel 238' which is joined to the panel 234' at a fold line 240', and a side

flap 242' which is joined to the panel 238' at a fold line 244'. A top flap 228 is joined to the panel 214 at a fold line 230. Adhesive is applied to one surface of the blank 212 as shown in FIGURE 6 at 248, 250, 252, and on 242; and at 250', 252', 254', and on 242'.

When the paper blank is folded and glued the fold line 236 forms the vertex of a first externally directed fold, the fold line 240 forms the vertex of a mediate, internally directed fold, and the fold line 244 forms the vertex of a second externally directed fold, to comprise the left plait 232. The right plait 232' is similarly comprised. The left and the right edges of the baffle panel 220 are respectively disposed in the first folds of the left and the right plaits, as shown in FIGURE 7, but are not joined thereto. The baffle panel 220 and the panel 214 form a sub-enclosure which is adapted to receive a plurality of documents, here shown as a single document 256.

An indicium 257, here shown as a postage stamp, is disposed on the panel 214. Additional indicia, here shown as notches 258 and 260, and 258' and 260', are respectively cut into the left plait 232 and the right plait 232'. The indicium 257 may be sensed by the depository machine to orient the panel 214, while the other indicia may be sensed to orient the plait which is to be initially opened by the opening means of the depository machine.

The use of the impression transfer agent 262 for providing a duplicate sender's address and itemized list of the enclosed documents is similar to that previously described with respect to the first embodiment.

This second embodiment is utilized in a manner similar to that for the first embodiment, the documents are inserted into the sub-enclosure provided by the baffle panel 220 and the panel 214. When the envelope is received by the depository machine, either end may be initially opened, thereby minimizing the maximum rotation and adjustment that may have to be applied to the envelope to properly present it to the depository machine.

An additional modification of this invention is shown in FIGURE 9. In this modification the two folds of each plait of the envelope are formed of unequal width. Thus, in the exemplary case of the plait 332, the fold including the fold line 336 which receives the baffle panel 320 and the document 356 is made narrower than the fold including the fold line 344. The plait 332 may be spread apart, to receive the dagger-like element at the fold line 340, by a projecting arm which engages and depresses the wide fold and not the narrow fold.

It is thus apparent that the envelope of this invention is ideally adapted for transmitting certain types of documents which can be extracted from the envelope, and be suitably processed subsequent to such extraction, all this being accomplished without human intervention.

While certain embodiments of this invention have been shown and described, it will be apparent to those skilled in the art that other modifications may be made without departing from the principles of this invention which shall be limited solely by the scope of the appended claims.

I claim:

1. An envelope comprising:
a first and a second substantially symmetrically quadrilateral outer panel;
each of three of said laterals of said first outer panel having a juncture with a corresponding lateral of said second outer panel, said outer panels thereby forming an enclosure;
one of said outer panels having a flap attached to said fourth lateral thereof for overlying said other of said outer panels for providing a juncture between said fourth laterals and thereby closing said enclosure;
- a quadrilateral baffle panel disposed within said enclosure and substantially coextensive with the interior of said enclosure;
- said fourth lateral of said second outer panel having a

juncture with the adjacent lateral of said baffle panel; said baffle panel dividing said enclosure into a first and a second chamber; said first chamber being formed by said baffle panel and said first outer panel and having an aperture at 5 said fourth lateral of said first outer panel, and adapted to receive documents therethrough; said second chamber being formed by said second baffle panel and said second outer panel and being inaccessible at all of said laterals of said outer panels; 10 one of said junctures between said first and said second outer panels including a plait having a first externally directed fold adjacent said first outer panel, a second externally directed fold adjacent said second outer panel, and therebetween an internally directed 15 fold; said first and said second externally directed folds being partially sealed along the direction of the major axis of said folds to impart rigidity to said folds; one of said laterals of said baffle panel being freely disposed within the open portion of said first externally directed fold; 20 whereby when an opening means is thrust through said internally directed fold, the opening means is guided by said baffle panel into said second chamber. 25

2. An envelope for use in conjunction with a depository apparatus which is provided with means for receiving and for opening an envelope and for freeing articles contained therein, said envelope comprising:

a pair of four-sided panels forming a front and a back 30 panel respectively, said panels joined to one another along three sides to provide an enclosure; each of the joints along two opposite ones of said sides including respectively a fluted fold having a vertex 35 reaching into said enclosure and two vertices, substantially coextensive with said sides, constituting the lateral limits of said envelope; said fold along said two vertices being partially sealed along the direction of the major axis of said folds to impart rigidity to said folds; 40 a baffle disposed within said enclosure juxtaposed on one panel and terminating laterally in the open portion of said respective folds and arranged relative to said folds to cause articles inserted into said enclosure from the fourth side to be disposed between 45 one of the panels and said baffle, and to cause opening means inserted into the envelope at said vertex to be disposed between said baffle and the other panel whereby the baffle acts as a shield for articles disposed in said enclosure.

3. An envelope comprising: a first and a second substantially symmetrically identical quadrilateral outer panel; each of three of said laterals of said first outer panel 50 having a juncture with a corresponding lateral of said second outer panel, said panels thereby forming an enclosure;

one of said junctures including a plait having a first externally directed fold adjacent said first outer panel, a second externally directed fold adjacent said second outer panel, and therebetween an internally directed fold, one of said externally directed folds being of greater width than the other of said externally directed folds; a quadrilateral baffle panel disposed within said enclosure and substantially coextensive with the interior of said enclosure, said baffle panel and said first outer panel forming a sub-enclosure for receiving documents; one of said laterals of said baffle panel being freely disposed within said first externally directed fold. 4. An envelope comprising: a first and a second substantially symmetrically identical quadrilateral outer panel; each of three of said laterals of said first outer panel having a juncture with a corresponding lateral of said second outer panel, said panels thereby forming an enclosure; each of the junctures along two opposite ones of said laterals including a plait, each of said two plaits having a first externally directed fold adjacent said first outer panel, a second externally directed fold adjacent said second outer panel, and therebetween an internally directed fold, one of said externally directed folds being of greater width than the other of said externally directed folds; one of said outer panels having a flap attached to said fourth lateral thereof for overlying said other of said outer panels for providing a juncture between said fourth laterals and thereby closing said enclosure; a quadrilateral baffle panel disposed within said enclosure and substantially coextensive with the interior of said enclosure, said baffle panel and said first outer panel forming a sub-enclosure for receiving documents; one of said laterals of said baffle panel being freely disposed within said first externally directed fold of one of said plaits, and another of said laterals of said baffle panel being freely disposed within said first externally directed fold of the other of said plaits.
